(57) **CLAIM**

The ornamental design for a automotive diagnostic labscope and gas analyzer, as shown and described.

DESCRIPTION

FIG. 1 is a front right perspective view of the automotive diagnostic labscope and gas analyzer;

FIG. 2 is a front left perspective view of the automotive diagnostic labscope and gas analyzer;

FIG. 3 rear perspective view of the automotive diagnostic labscope and gas analyzer;

FIG. 4 is a right side elevational view thereof;

FIG. 5 is a front elevational view thereof;

FIG. 6 is a top plan view thereof;

FIG. 7 is a bottom plan view thereof; and,

FIG. 8 is a rear elevational view thereof.

The broken line showing is for illustrative purposes only and forms no part of the claimed design.
